SPECIFICATION.

I, SAMUEL P. ROBINSON, of Plainfield, in the county of Windham and State of Connecticut, have invented and produced a new and original Design for a Portable Cooking-Range.

The nature of my design is fully represented in the accompanying photographic illustration, to which reference is made, and consists in the manner and form of the word *Ætna* upon the door, and the style of the figure thereon and on the panels and doors, making a border of raised

work thereon, having reference to its peculiar style and shape, with the raised figure on the legs of the same.

I claim as my invention—
